UNITED STATES PATENT OFFICE.

VICTOR C. VAN'T WOUD, OF NEW YORK, N. Y.

SYRINGE-PIPE.

SPECIFICATION forming part of Letters Patent No. 737,795, dated September 1, 1903.

Application filed May 18, 1903. Serial No. 157,635. (No model.)

To all whom it may concern:

Be it known that I, VICTOR C. VAN'T WOUD, a citizen of the United States, residing at New York, in the county of New York and State of New York, have invented certain new and useful Improvements in Syringe-Pipes; and I do hereby declare the following to be a full, clear, and exact description of the invention, such as will enable others skilled in the art to which it appertains to make and use the same.

My invention relates to syringe pipes or tips, and has for its object to produce such pipe-tips which will be adapted to throw a circular spray in either a forwardly or backwardly direction, as desired. To accomplish this result, I employ the new and novel construction hereinafter fully and clearly described and illustrated.

In the drawings, Figure 1 is a side or longitudinal view of my improved construction when adapted to throw a forwardly-extending spray. Fig. 2 is a longitudinal sectional view of the same. Fig. 3 is a longitudinal sectional view of my construction when adapted to throw a backwardly-extending spray. Fig. 4 is a perspective view of the parts of the spray attachment. Fig. 5 is a perspective view of the end of my improved pipe.

In the drawings like letters of reference designate similar parts of my construction.

A in the drawings represents a hard-rubber tube of suitable size and shape with either a plain or fluted exterior surface, said tube having one end closed or sealed and having its other end attached to a syringe by any suitable means, as the rubber tube B. This tube A is provided near its closed end with an annular groove *a* and outlet holes or ports *a' a'* in said groove *a*. C is an attachment, preferably oval-shaped, adapted to tightly fit on said tube in such a manner as to cover the groove *a* and outlet-holes *a' a'*. This attachment C preferably comprises two interlocking portions *c c*, as shown in Fig. 4; but, if desirable, it may be constructed in one piece. *c c* are each provided with suitable threads *c' c'*, adapted to engage similar threads *a' a'* on the tube A to retain said attachment C in position on said tube and to enable it to be reversed when desirable. Said oval attachment C is provided at its center with an an-

nular groove *c²*, the sides of said groove being preferably oblique. *c³ c³* are passages in the attachment connecting the grooves *a* and *c²*. Thus when liquid is admitted to the tube A from a syringe it passes to the closed end of said tube and is forced through the holes *a' a'* into the groove *a*, then through the hole *c³ c³* into the obliquely-extending groove *c²*, from which it is thrown in the form of a spray either in a forwardly or backwardly extending direction, according to the manner in which the attachment C is placed on the tube A, and it is obvious that the direction of the spray may be easily regulated, as desired, by reversing the attachment C on said tube A.

What I claim, and desire to secure by Letters Patent, is—

1. In a device of the class described, the combination with a tube, of a reversible spray attachment detachably secured to said tube and having a discharge inclined to the longitudinal axis of the said attachment, whereby the direction of the spray is controlled by reversing said attachment, substantially as described. 70

2. In a device of the class described, the combination with a tube closed at its outer end, and provided with lateral discharge-apertures, of a reversible spray attachment having a central longitudinal aperture to fit over said tube and provided between its ends with a lateral discharge inclined to the longitudinal axis of said attachment, and adapted to communicate with the lateral apertures in said tube, substantially as described. 80

3. In a device of the class described, the combination with a tube closed at its outer end, and having a threaded portion and lateral discharge-apertures between the threaded portion and the outer end, of a reversible spray attachment having a central longitudinal aperture to fit over said tube and threaded at each end to engage the threaded portion thereof, said attachment being provided with a lateral discharge between its ends, inclined to the axis of the said attachment, and adapted to communicate with the lateral apertures of said tube, substantially as described. 90

4. In a device of the class described, the combination with a tube closed at one end and provided with an annular groove and outlet-ports in said groove, of an attachment pro-

vided with a suitable annular groove and outlet-ports in said groove and in communication with the groove in said tube, said attachment being adapted to be reversed, substantially as and for the purpose described.

5. In a device of the class described, the combination with a tube closed at one end and provided with an annular groove and outlet-ports in said groove, of an attachment provided with an obliquely-extending annular groove and outlet-ports in said groove, said

ports being in communication with the groove and outlet-ports in said tube, said attachment being adapted to be reversed, substantially as and for the purpose described.

15

In testimony whereof I affix my signature in the presence of two witnesses.

VICTOR C. VAN'T WOUD.
